APPAREL HANGER

David H. Lindemann, 228 SW. 21st Terrace,
Fort Lauderdale, Fla. 33312

Filed Aug. 23, 1972, Ser. No. 283,046

Term of patent 14 years

Int. Cl. D6—08

U.S. Cl. D6—116

FIG. 1 is a front view of the apparel hanger, showing my new design;

FIG. 2 is a side view thereof.

I claim:

The ornamental design for an apparel hanger, as shown.
